UNITED STATES PATENT OFFICE.

WILLIAM V. HUNT, OF NORTH VANCOUVER, BRITISH COLUMBIA, CANADA.

PERFORATED-PAPER-ROLL HOLDER.

Application filed June 16, 1926. Serial No. 116,449.

My invention relates to improvements in 5 perforated paper roll holders which are particularly adapted for dispensing single strips of paper from toilet or towel rolls or the like. The objects of the invention are to provide means whereby the end of a strip of paper is released from contact with the roll of which it forms a part, and whereby it is projected outwardly from the roll in 10 such a manner that its free end may be conveniently grasped by the user, and the strip torn from the roll. A further novel object is to utilize a flow of air to effect the releasing of the strip so that the release is effected 15 throughout the length of the roll.

The invention consists essentially of an open faced casing in one end of which a panel is fulcrumed, said panel having a nozzle communicating with the casing which 20 is adapted to discharge a flow of air under the free end of the paper forming a paper roll, supported from the face of the panel, as will be more fully described in the following specification, in which:—

25 Fig. 1 is a front view of the invention.

Fig. 2 is a sectional view showing the panel and its paper roll in forward or normal position.

30 Fig. 3 is a sectional view showing the panel and its paper roll in depressed position with the free end of the roll dislodged.

In the drawings like characters of reference indicate corresponding parts in each figure.

35 The numeral 1 indicates generally a casing having a rear wall 2, a top wall 3, side walls 4, a bottom grooved strip 5 and a top front stop 6. Fulcrumed in the bottom grooved strip 5 is a panel 7 which substantially fits the front of the casing and is capable of being depressed into contact with the rear wall 2 and which is adapted to fall 40 forwardly, by gravity, as shown in Figure 2.

Suitably mounted upon the front of the 45 panel 7 is a bracket 8 supporting a transversely disposed form 9 upon which the roll of paper is adapted to be carried. The panel is provided with a nozzle 10 having an elongated outlet 11 at its upper end which is 50 preferably so disposed as to discharge at the rear of the form 9 adjacent its longitudinal centre, the nozzle communicates with the casing 1 through an aperture 12.

The numeral 13 indicates a roll of paper 55 perforated transversely as at 14 to divide the paper of the roll into a plurality of con-

nected strips 15. When the device is used in public places where it is desirable to provide against improper removal of the paper rolls, I may provide locking means upon the 60 free end of the form 9 or in any other suitable position.

Having thus described the several parts of my invention I will now briefly explain its function.

The paper roll 13 is pressed onto the form with the free end of the outer strip 15 hanging downwards between the roll and the panel 7, the free end of the strip terminating slightly above the outlet 11 of the jet 10. 70 When a strip of paper is desired, the finger tips are pressed against the panel 7 just below the nozzle 10 to move the panel rearwardly into the casing 1. The air displaced by the inward movement of the panel flows 75 through the nozzle 10 and impinges upon the roll 13 dislodging the free end of the strip 15 from its contact with the next strip on the roll and forces it upwards towards the top wall 3 of the casing, where it is 80 again brought under the influence of a further current of air expressed from the casing between the upper extremity of the panel 7 and the top wall 3. This air current suffices to completely unwrap the strip from the roll 85 and if the hand is held with the palm upwards, when depressing the panel, the free end of the strip will fall therein when it can be conveniently gripped between the fingers and thumb, and torn from the roll at 90 the perforations 14.

What I claim as my invention is:

1. In combination, a holder for a roll of material, means for directing a fluid agent toward one portion of the roll to effect initial dislodgment of the free end of the roll and means for directing a fluid agent toward another portion of the roll to impinge against the free end of the roll subsequent to the initial dislodgment thereof.

2. The combination of a casing having rear, top, bottom and side walls, a panel normally closing the front of the casing and spaced from the rear wall to form an intervening air chamber, the lower edge of said panel being supported on the bottom wall to form a pivot about which the panel may be swung to or from the said rear wall, a roll holder carried by the outer side of said panel, a nozzle carried by an extending upwardly from an opening formed in the panel below said roll holder, said nozzle

having its discharge end terminating below the upper plane of the roll holder, the upper edge of said panel being spaced from the top wall of the casing to permit a current of air to pass outwardly and over said upper edge during rearward movement of the panel, said current of air being directed toward the

upper edge of the roll holder to assist the current of air passing outwardly through said nozzle in dislodging the free end of the material carried by the roll holder.

Dated at Vancouver, B. C., this 4th day of June, 1926.

WILLIAM V. HUNT.
